UNITED STATES PATENT OFFICE.

EUGÈNE HENRI TARTRAIS, OF MAISONS-LAFFITTE, FRANCE.

INTERNAL-COMBUSTION ENGINE.

Application filed July 14, 1921. Serial No. 484,807.

To all whom it may concern:

Be it known that I, EUGÈNE HENRI TARTRAIS, citizen of the French Republic, residing at Maisons-Laffitte, in the Republic of France, have invented new and useful Improvements in Internal-Combustion Engines, of which the following is a specification.

This invention relates to improvements in internal combustion engines working with injection of liquid fuel, of the type wherein the piston is provided with an extension adapted to engage in an aperture connecting the cylinder with the combustion chamber. One of the characteristics of this invention resides in the fact that the said extension of the piston is traversed by one or more ducts opening on the one hand at the side of the said extension and on the other hand upon the upper surface thereof, and through which a small portion of the air or fuel mixture compressed by the piston is enabled to pass when the said extension is engaged in the above-mentioned aperture.

In the accompanying drawing which shows by way of example an embodiment of this invention:

Fig. 1 is a section of the upper part of the cylinder and the piston of a two cycle engine.

Fig. 2 shows a modified form of the obturator.

As shown in the drawing, the piston 1 working in the cylinder 2 is provided with a central extension 4. Upon the end of cylinder 2 is mounted the cylinder head 2^a closed by a cover 16. The combustion chamber 8, which has the shape of a torus, is secured in the cylinder head by an annular screwthreaded member 6 into which the extension 4 on the piston is adapted to engage, at the end of the compression stroke, an annular space 9 being then left between the two members. The upper central part 40 of the cover 16 is provided with a water circulation 17 and carries the fuel atomizer 11, which is adapted to discharge the fuel radially in all directions.

The piston 1 is shown in full lines in the position which it occupies in the upper part of the cylinder 2 somewhat before reaching the dead point, and in broken lines when at the dead point itself. When at the bottom of its stroke, the piston 1 has 55 opened and closed the air ports not shown for the admission of scaveng-

ing air and the cylinder 2 has received the necessary quantity of air which is compressed upon the return of the piston. When the piston reaches the position shown in full lines, that is, when the edge 3 of the extension or deflecting obturator 4 disposed upon the piston comes to a level with the edge 5 of the member 6, the compressed air retained in the chamber 7 temporarily formed between the piston and the cylinder head is caused to pass in a violent manner into the combustion chamber 8 through the annular space 9 between the parts 4 and 6, and assumes a whirling motion according to the arrows 10. While this transfer of fluid is taking place, the atomizer 11 will project the liquid fuel according to the arrows 12 in equal quantities about the axis thereof. This liquid fuel is taken up by the stream of air 13 in the form of an annular column which issues from the annular orifice 9 and said fuel is drawn into the fluid in movement as shown at 10. The more volatile portions are at once evaporated and become mixed with the air. The portions still in the liquid state are projected by centrifugal force against the walls of the chamber 8 which are highly heated, and in fact to redness, inasmuch as no water cooling is provided in said chamber, and the said fuel portions become vaporized in turn and the gas thus produced will enter the moving mass 10. In these conditions, under the combined action of the heat of compression and the heat of the walls, the ignition takes place, giving rise to a substantially isopleeric combustion. The cycle is then completed in the known manner.

Experience shows the following drawback in this method of operating. In practice, it is most probable that the transfer of fluid from the portion 7 of the cylinder into the space 20 in the combustion chamber is not carried out in a continuous manner but perhaps with slight undulatory or return movements occasioned by an early partial combustion of fuel from the beginning of the injection. Furthermore, the hatchet portion shown in the figure at the inner part of the "air tube" 13 constitutes a relatively calm region. It may thus be supposed that a portion of the fuel already injected and not consumed may be accidentally brought into the said region and the quantity thereof will be too considerable to permit of encountering sufficient comburant

for the same at this point, and moreover the said fuel will not be in the proper condition for a good combustion, having therein particles which are still in the liquid state.

5 The present invention has for its purpose to obviate this drawback. To this end, the obturator 4 is constructed as shown in Fig. 1 and is provided with ducts 15 constituting a slight by-pass from the main stream which 10 passes through the annular orifice 9. This slight branch has a scavenging action and causes the badly-directed fuel to return to the moving mass of gases 10. It is obvious that the said ducts may assume various 15 shapes, and they may be given for instance the form shown in Fig. 2 or another form which will carry out the same purpose, this being to reduce the speed of the air at the outlet. A violent rush of air upon the atomizer would have the effect of projecting the fuel upon the wall at 16, this being a cold portion—due to the water circulation at 17—which is contrary to the proposed 20 purpose.

25 In the two examples herein set forth, it is observed that the speed of the air in the branch stream is reduced, this being effected in Fig. 1 by the converging position of the ducts 15 and in Fig. 2 by using a small 30 expansion chamber 18 provided with relatively large discharge apertures 19.

Having now described my invention, what I claim as new and desire to secure by Letters Patent is:

35 1. An internal combustion engine comprising a cylinder, a combustion chamber having the shape of a torus and communicating with said cylinder by a central opening, a fuel atomizer extending into said combustion chamber opposite said central opening 40 and adapted to discharge the fuel in radial

directions, a piston working in said cylinder and a projection on the head of the piston, adapted to engage into said central opening, said projection being provided with 45 means affording a restricted passage for the air surrounding the projection, which passage opens into the end face of the projection.

2. An internal combustion engine comprising 50 a cylinder, a combustion chamber having the shape of a torus and communicating with said cylinder by a central opening, a fuel atomizer extending into said combustion chamber opposite said central opening 55 and adapted to discharge the fuel in radial directions, a piston working in said cylinder and a projection on the head of the piston, adapted to engage into said central opening, said projection being provided with 60 ducts which extend therethrough from the side surface of said projection to its end face.

3. An internal combustion engine, comprising a cylinder, a combustion chamber 65 having the shape of a torus and communicating with said cylinder by a central opening, a fuel atomizer extending into said combustion chamber opposite said central opening and adapted to discharge the fuel in radial 70 directions, a piston working in said cylinder and a projection on the head of the piston, adapted to engage into said central opening, said projection being provided with ducts which extend therethrough from the 75 side surface of said projection to its end face and converge towards each other on this end face.

In testimony whereof I have signed my name to this specification.

EUGÈNE HENRI TARTRAIS.
